UNITED STATES PATENT OFFICE.

FRANK J. M. CURRAN, OF GREENVILLE, MICHIGAN.

METAL-COVERED REFRIGERATOR.

Application filed May 7, 1921. Serial No. 467,544.

To all whom it may concern:

Be it known that I, FRANK J. M. CURRAN, a citizen of the United States of America, residing at Greenville, in the county of 5 Montcalm and State of Michigan, have invented certain new and useful Improvements in Metal-Covered Refrigerators; and I do hereby declare the following to be a full, clear, and exact description of the invention, such as will enable others skilled in the art to which it appertains to make and use 10 the same.

This invention relates to refrigerators. It is primarily concerned with metal covered 15 refrigerators, the metal usually being provided with porcelain coatings baked thereon on the outer side whereby the refrigerator presents a particularly attractive appearance. By covering the refrigerator with 20 metal, expensive finishing lumber is not needed, nor is the operation of staining and finishing the outside of the refrigerator casting required. It is a primary object and purpose of the present invention to provide 25 a novel construction of metal covering for refrigerators which may be bent and formed readily to shape, novel corner constructions being provided which are readily welded without warping of the metal and which do 30 not warp out of shape during the operation of baking the porcelain thereon, together with a novel front construction of porcelain covered metal which is not directly joined with the top and side covering for the 35 refrigerator so as to be liable to break and chip the porcelain at the joining points, but which has abutting contact therewith at different points, the line of separation in all cases being covered and concealed by a novel 40 covering strip or the like, whereby the outside appearance of the refrigerator is attractive and is not liable to deterioration through chipping of the porcelain at certain points where strain would come in an integral construction. Various other objects 45 and purposes are served at the same time, particularly with respect to the item of cost of production which is lessened very materially by my invention.

50 For an understanding of the invention and the constructions embodying the same, reference may be had to the following description, taken in connection with the accompanying drawings, in which,

55 Fig. 1 is a perspective view of the metal

covered refrigerator of my invention, the doors thereof being removed.

Fig. 2 is a fragmentary perspective view, illustrative of the corner formation for the cover of the refrigerator and the method 60 by which it is made.

Fig. 3 is a plan of the blank used to make the top and side covering for the refrigerator, said blank also covering, when formed, portions of the front and back of the re- 65 frigerator.

Fig. 4 is an elevation of the remaining front members used for the refrigerator cov- 70 ering at the front.

Fig. 5 is a front elevation of the refrig- 70 erator covering members in the position which they occupy on the refrigerator when in use, the joint covering devices not being shown.

Fig. 6 is a fragmentary enlarged hori- 75 zontal section through a refrigerator made in accordance with my invention, and

Figs. 7, 8 and 9 are perspective views of the various finishing and joint covering members used at the front of the refrig- 80 erator.

Like reference characters refer to like parts in the different figures of the drawings.

The major portion of the metal covering 85 is of a single blank of sheet metal having a central section 1 to cover the top of the refrigerator, and two end sections 2 to cover the sides, the line of bending being that indicated at 3 whereby a substantially U- 90 shaped form is made which will slip downwardly over the outside of the refrigerator. In one edge of this blank two substantially rectangular recesses or notches 4 are cut connecting with which are arrow shaped notches 95 5 located directly at one end of each of the lines of bending 3, as shown. The blank, before it is bent into said U-shape is first bent longitudinally along the line 6 so as to position the central portion 7 between the 100 two recesses 4, and the end portions 8 substantially at right angles to the plane of the main body of the blank. Likewise at the opposite edge of the blank, two similar but smaller rectangular recesses 9 are made in the blank, joining with arrow-shaped notches 10 positioned directly opposite the notches 5 and at the other ends of the fold lines 3. The blank is also bent longitudinally along line 11 before folding into U-shape and in 110

the same direction as the parts at the other side edge of the blank, forming a central portion 12 and the end portions 13 lying substantially at right angles to the plane of the main body of the blank. When the blank is folded into U-shape, it is evident that the notches at 5 and 10 close and that the recesses at 4 and 9 are also closed, the inner ends of the parts 8 and 13 coming against the under edges of the central sections 7 and 12 at the ends thereof, and the ends of said central sections 7 and 12 abutting against the forwardly turned narrow strips 8^a and 13^a, as shown at 14 and 15, respectively. These abutting parts are very easily welded and no line of separation will appear at such lines 14 and 15, an integral effect and actual integral structure being made. The outer sides of the cover thus formed is covered with porcelain, preferably, and the welding lines will be completely covered and obliterated as thus covered. This covering is very easily handled both in the welding and porcelain covering operations, not warping, or cracking under the heating and shrinking due to the heat treatment necessary therefor.

The cover thus made may be placed over, from above, the refrigerator casing, the top 7 lying against the top of the casing and ends 2 against the ends 16 of said casing. The section or flange 12 and the similar vertical portions 13 come against the back 17 of the casing, while the horizontal downwardly projecting flange 7 passes in front of the top, the vertical flanges 8 lying against and in front of the side posts 18 at each side of the refrigerator casing. (See Fig. 6.) At each rear vertical corner of the casing a vertical post 19 is located for connection of the back and ends of the casing thereto and a refrigerator lining 20 is located within the casing between which and the back, sides and top of the casing, in the spaces at 21, the usual insulating material and insulating construction is located. The open front side of the refrigerator casing has a vertical post 22 disposed substantially midway between the side posts and there is usually a division of the space within the casing into provision compartments 23 and 24 and an ice chamber 25, a suitable horizontal cross member being disposed between the post 22 and one of the side posts 18 at the lower edge of the ice chamber, a well known and common construction in refrigerator manufacture. The refrigerator also is necessarily provided with a bottom, usually set a short distance above the floor.

To cover the front sides of the post 22, the front edge of the bottom and the cross piece at the lower side of the ice chamber three pieces of sheet metal 26, 27 and 28 are used and arranged with respect to each other as shown in Figs. 4 and 5, plate 26 being vertically disposed with its lower end

against the upper edge and between the ends of the lower plate 27, the line of contact of said plates being at 29, and the plate 28 lying above plate 27 and abutting at 30 at one end against a side edge of plate 26. 70 These plates of sheet metal are welded together at 29 and 30 and the structure thus formed is set in against said post 22 and other parts named, the ends of the lower plate 27 coming to the edges of the flanges 75 8, the upper end of plate 26 coming to the under edge of the flange 7 between its ends and the free end of the plate 28 coming to the edge of the flange 8 at one side of the cover, as shown in Fig. 5. These joints 80 are not welded or otherwise connected, but the connected plates 26, 27 and 28 are porcelain covered on their outer sides and then placed in position, being secured and the open joints covered by means which will 85 now be described.

At each side of the refrigerator a metal strip in the shape of an angle iron is placed, comprising two legs 32 and 31 positioned at right angles to each other, the inwardly extending leg 31 being cut at certain points and the metal left in the same plane with the outside leg 32. In the strip used at the left-hand side, in Fig. 1, two of the cuts are made in leg 31 to leave two projecting 95 parts 33 which extend over the adjacent free ends of the plates 27 and 28. The leg 31 passes along the inner side of post 18 and is secured thereto by screws or similar fastenings. At the opposite side only one 100 of the projecting parts 33 is required to cover the free end of the lower plate 27. In both cases the outer legs 32 overlap the adjacent portions of flanges 8. At the upper side of the front of the refrigerator, a similar strip is used having an outer leg 32^a overlapping the edge of the flange 7 and with a central downwardly projecting portion 33^a to cover the free end of the vertical plate 26. The plate 26 is secured to the post 22 110 by angle pieces having inwardly extending legs 34 lying alongside of the post at each side and secured by screws, and outer legs covering the edges of the plate as shown in Fig. 1. It is of course apparent that the 115 angle piece must be divided on the side of the post next adjacent the ice chamber, and the upper end of each angle piece has the leg 34 extended, as indicated at 34^a, as it passes farther upward than the leg 35 due 120 to the projecting portion 33^a. At the lower sides of the ice chamber and of the provision compartments angle pieces with inwardly extending legs 36 and downwardly extending legs 37 are used, the same being extended 125 at opposite ends, as indicated at 38 and 39 to make a finished appearance and fit with the other finishing strips, and the lower side of the division between the ice chamber and the provision compartment below it is 130

likewise finished with a similar strip, merely reversed as to position. The side edges of all of the plates 26, 27 and 28 are thus covered and secured in place by metal securing strips which line and border the door openings to the various chambers to the refrigerator, the doors, one of which is shown at 40 covering said finishing strips when in closed position and concealing them from view. The doors are likewise metal covered by a covering 41 which is also porcelainized on its outer sides.

The finishing strips may be of any suitable metal finish, burnished, nickel plated, or otherwise. The construction described is very practical, each of the parts to be porcelain covered being of a shape and form making such process easy without distortion or warping of the same. The free position of 20 the plates 26, 27 and 28 with respect to the remainder of the structure is a valuable feature, there being no strain present or liability to strain and distortion such as would be sure to occur if the same were connected 25 and the same put through a porcelain covering process. The joints between the same are fully covered and out of sight, and the appearance and finish of the refrigerator is enhanced rather than diminished. There 30 are no strains to which the completed structure is subjected which will cause breaking or chipping of the porcelain. The cost of manufacture is low due to the simplicity of the construction and to the elimination of 35 difficult problems of porcelain covering.

The appended claims define the invention, and I consider myself entitled to all forms of structure coming within their scope.

I claim:

10 1. A metal covering for refrigerators, comprising an elongated blank of sheet metal having two rectangular shaped recesses at directly opposite points in the side edges thereof and bent into substantially U-shape 45 on lines extending between said recesses, and also bent lengthwise thereof on lines set in from the side edges of the blank a distance slightly greater than the depth of the recesses, the abutting edges of the metal at 50 said recesses being connected by welding, substantially as described.

2. A metal covering for refrigerators, comprising an elongated blank of sheet metal having two rectangular shaped recesses in 55 each side edge of the blank at directly opposite points therein, said recesses having substantially arrow-shaped extensions at their inner portions and adjacent one end, the blank being bent into substantially U-shape 60 on lines connecting said arrow-shaped extensions to the recesses, and also bent lengthwise on lines set in from the side edges of the blank a distance slightly greater than the depth of the recesses, the abutting edges 65 of the metal coming together at such re-

cesses when thus bent being connected by welding, substantially as described.

3. A metal covering for refrigerators comprising a blank of sheet metal bent into substantially U-shape and provided with 70 downwardly and inwardly extending flanges at one side to cover the front side of the top of the refrigerator and the side posts thereof, a flat metal member comprising a vertical plate, a horizontal plate welded thereto at its 75 lower end and a second horizontal plate above the first plate welded to the vertical plate at one end, said member being located at the front side of the covering between said flanges and in the same plane therewith and 80 disconnected from said flanges, and finishing strips attached to the refrigerator lining the door openings and covering the open joints between said metal member and the U-shaped member, substantially as described. 85

4. In combination, a refrigerator casing having top, bottom sides and back and an open front, a vertical post disposed between the top and bottom substantially midway between the sides, a cross member disposed 90 between the post and one of the sides above the bottom, a metal covering for the casing of substantially U-shape covering the top and sides and having flanges at its front portion covering the front sides of the top 95 and of the sides of the refrigerator, a metal member comprising a flat vertical plate, a lower horizontal plate welded between its ends to the lower end of the vertical plate, and a second horizontal plate welded at one 100 end to a side edge of the vertical plate and located above the first horizontal plate, said member lying against the post, the front side of the bottom and said cross member in the same plane with the flanges of the U-shaped 105 covering, and metal finishing strips lining the openings in the front of the refrigerator for securing said metal member in place, covering the open joints between the ends of the plates comprising said metal member and 110 the flanges of the said covering and covering the free edges of said plates making up said metal member, substantially as described.

5. A refrigerator construction containing 115 the elements in combination defined in claim 4, in which said metal finishing members comprise angle members one leg of which extends inwardly into the front openings of the refrigerator and through which fastening devices pass into the refrigerator casing, the vertical post, and cross member, and the other leg overlaps and covers adjacent edges of the said flanges and said plates making up said metal member, substantially as described. 120

6. A refrigerator construction, comprising an inclosing casing having a front open side, partitions or posts dividing said open side into door openings, a metal covering for 130

the casing at the top and sides having flanges projecting over the front of the refrigerator casing to said front opening, a separate metal member lying against the front side 5 of the bottom of the casing and said post and partition, and metal finishing members attached to the refrigerator at the top, bottom and sides of said door openings having portions extending over the edges of said 10 separate metal member and said flanges, and covering the open joints between the adjacent portions of said covering and separate metal member, substantially as described.

7. A covering for refrigerator casings 15 formed from an elongated blank of sheet metal having two spaced apart rectangular recesses cut in one edge thereof, the blank being bent longitudinally substantially at right angles along a line paralleling the

edge of the blank and set in a distance 20 slightly greater than the depth of the recesses, and then bent into substantially U-shape on transverse lines extending across the blank from said recesses, the recesses closing with said bending and bringing 25 edges of the metal at said recesses into abutting engagement for welding, substantially as described.

8. A metal covering for refrigerators comprising two separate metal members 30 adapted to lie against a refrigerator casing and cover the same, and finishing strips of metal for securing said members to the casing, covering the open joints between them, and lining the front door openings to the 35 casing, substantially as described.

In testimony whereof I affix my signature.

FRANK J. M. CURRAN.
